MINING MACHINE

Frederick W. Vodez, Wilmette, Ill., assignor to
 Goodman Manufacturing Company, Chicago,
 Ill., a corporation of Illinois

Application August 11, 1930, Serial No. 474,411
 Renewed November 22, 1933

17 Claims. (Cl. 262—28)

This invention relates to improvements in mining machines and has for its principal object to provide a new and improved means for efficiently removing the cuttings from the path of the cutter chain, which may be applied either to a machine of the truck mounted type adapted to cut an arcuate kerf at or near the mine bottom, or to a machine of the longwall or continuous cutter type.

10 A companion application, filed herewith, discloses a portable hand controlled device particularly adapted for removing cuttings from the path of the cutter chain, but in which the device is mounted on wheels for movement on the ground. While the general principle of the device in my present application is similar to that of my companion application, the device of my present application is directly supported on the mining machine and is movable thereon to eventually distribute the cuttings on the mine floor and to regulate the angle of the conveyor with respect to the cutter chain in order that a maximum amount of cuttings may be gathered in all positions of the cutter bar with respect to the mining machine proper.

25 My invention may be more clearly understood with reference to the accompanying drawings wherein:

Figure 1 is a fragmentary perspective view of 30 a mining machine having the device of my invention attached thereto with parts of the device embodying my invention broken away and in section;

Figure 2 is a fragmentary top plan view of 35 a mining machine showing the device embodying my invention connected thereto and in a different position than is shown in Figure 1;

Figure 3 is a top plan view of the device 40 embodying my invention showing the cuttings gathering means supported in an inoperative position on the mining machine for movement about the mine;

Figure 4 is a sectional view taken on line 4—4 of Figure 2; and

45 Figure 5 is a fragmentary perspective view of the forward end of the conveyor trough.

In the embodiment of my invention illustrated, my invention is shown as applied to a mining machine 3 of the truck mounted slabbing type which 50 is adapted to cut a kerf in the mine wall at the mine bottom or at various elevations with respect thereto. The mining machine herein illustrated is similar to that shown in a prior application bearing Serial No. 157,005, filed by William T. 55 McCullough, on December 25, 1926, which is now

Patent No. 1,891,719, and will not herein be described in detail excepting as to the parts which particularly pertain to my invention. The mining machine 3 is only partially shown in the drawings and includes a depending cutter head 4 vertically adjustable in guides 5 and having a cutter bar 6 projecting forwardly therefrom, which cutter bar has a cutter chain 7 movable thereabout in the usual manner.

Referring now to several of the novel features 65 of my invention, an arcuate cuttings deflector 8 depends from the cutter head 4. The arcuate deflector 8 extends from the forward advance portion of the cutter head 4 rearwardly and around said cutter head and opens to the retreating side of said cutter head. Said deflector substantially conforms to the path of the cutter chain 7 to deflect the cuttings discharged from said cutter chain from the retreating side of said cutter head and is held to said cutter head by 70 means of a bolt 9 and clips 10 secured to said cutter head.

A bracket 11 is fastened to the cutter head 4 on the retreating side thereof by means of bolts 12 and extends upwardly therefrom forming a support for the forward end of a cuttings gathering 80 and conveying device generally indicated at 13. A hook 14 depends from the outer end of the bracket 11 and has a collar 15 thereon abutting the top portion of said bracket which abuts a nut 85 16 threaded on said hook to hold said hook in position on the bracket 11 and allow for vertical adjustment of said hook.

The cuttings gathering and conveying device 90 13 includes a trough 17 having a spiral conveyor 18 rotatable therein. The forward end of the trough 17 is shaped like a shovel so as to engage the mine bottom and scoop up cuttings from the path of the deflector 8. A strap 19 extends across the sides of the trough 17 and has an eye piece 20 95 extending upwardly therefrom which may be hooked on the hook 14 for supporting the forward portion of said trough and the cuttings gathering and conveying device 13. A rearward portion 21 of the trough 17 is shaped so as to deflect cuttings 100 gathered by the spiral conveyor 18 away from the cutter chain 7 and opens on the left hand side of said trough.

Suitable means are provided for driving the 105 spiral conveyor 18 in the trough 17, which means herein comprises an electric motor 23 connected to the rearward end of the spiral conveyor 18 by means of a universal coupling 24 in a usual manner. The motor 23 is fixed to the trough 17 by means of a T iron 25 extending rearwardly from 110

- said trough and straps 26 which extend around said motor and are fastened to said T iron. Handles 27 and 28 are provided on the motor 23 to form a means for controlling the position of the 5 cuttings gathering and conveying device 13 with respect to the cutter head 4 and a push button control 29 is provided in the handle 27 for controlling operation of said motor in a usual manner.
- 10 Means are provided for adjusting the angle of inclination of the cuttings gathering and conveying device 13 with respect to the cutter head 4 and for supporting the rearward portion of said cuttings gathering and conveying device on the 15 mining machine which herein comprises a bracket 30 attached to the mining machine in a usual manner and having a rod 31 detachably connectible thereto at one end, which rod has a chain 32 connected to its opposite end. The chain 32 20 is connectible with a slotted bracket 33 fixed to the rearward end of the motor 23 and extending upwardly therefrom. The chain 32 is made up of a number of links so that any of said links may be connected to the slotted bracket 33 forming a 25 means for adjusting the angle of the trough 17 with respect to the cutter head 4.
- Suitable means are provided to hold the spiral conveyor 18 in the trough 17 when said conveyor is being driven by the motor 23, which means 30 herein comprise retaining strips 35 fixed to each inner side of the trough 17 and adapted to abut said spiral conveyor.
- The cuttings gathering and conveying device shown in my invention is so arranged that it may 35 be operated from the rearward end thereof or from a position remote from said rearward end. In order to operate this device in a position remote from the rearward end thereof, a hooked rod 37 is provided which may be hooked in one 40 of the links of the chain 32. This rod may be of any length to enable the operator of the mining machine to control the movement of the cuttings gathering and conveying device 13 or to enable another man to control the movement of said 45 cuttings gathering device. This makes it possible for the operator of said cuttings gathering chute to be out of the way of the cutter bar and operating end of the mining machine where conditions are such that it might be dangerous to operate 50 the device close to the cutting end of the mining machine; as, for instance, where the face is overhanging or top conditions are bad, or cutting conditions are such that the cutter bar is liable to jump out of the coal during the cutting operation.
- 55 When it is desired to move the mining machine 3 about the mine, the cuttings gathering and conveying device 13 may be hinged forwardly on the cutter head 4 and held in a forward position with respect to said cutter head by means of the rod 60 31 which may be connected to a bracket 38 on the opposite side of the mining machine from the bracket 30 as is illustrated in Figure 3.
- During the cutting operation the cuttings gathering and conveying device 13 is moved back- 65 wardly and forwardly about the axis of the hook 14 to efficiently gather the cuttings discharged from the cutter chain 7 in various positions of the cutter bar 6 with respect to the mining machine and to control the distribution of said cut- 70 tings to prevent accumulation of the cuttings in one large pile and evenly distribute them on the mine floor. Said movement of the cuttings gathering and conveying device 13 may be controlled by the handles 27 and 28 on the motor 23 or 75 the rod 37.

It may thus be seen that a simple and efficient power driven hand controlled means has been provided for gathering the cuttings discharged from a cutter chain; that this means is connectible with a mining machine and movable with respect thereto so as to gather a maximum amount of cuttings and distribute said cuttings evenly along the mine bottom; and that this means is so arranged that it may be supported in an inoperative position along the cutter head and cutter bar and take up a minimum amount of room when the mining machine is being moved from cutting place to cutting place.

Although I have herein shown and described one embodiment of my invention, it will be understood that the broad idea of a machine mounted conveyor may also be applied to types of mining machines other than that specifically disclosed, and that the construction and arrangement of the various parts may be altered without departing from the spirit and scope thereof. Furthermore, I do not wish to be construed as limiting myself to the specific form illustrated, excepting as it may be specifically limited in the appended claims.

I claim as my invention:

1. In combination with a track mounted mining machine having a depending cutter head, a cutter bar projecting forwardly therefrom having a cutter chain movable thereabout adapted to cut a kerf adjacent the mine bottom, and means wholly supported by said mining machine for clearing the cuttings from the path of said cutter chain comprising a spiral conveyor supported on said mining machine and attached to said cutter head adjacent the retreating side thereof for pivotal movement with respect thereto about a vertical axis.

2. In combination with a mining machine, a cutter head having a cutter bar projecting therefrom, a cutter chain movable thereabout adapted to cut a kerf adjacent the mine bottom, conveying means for clearing the cuttings from the path of said cutter chain comprising an inclined trough having a forward end engageable with the mine bottom and having a conveyor therein, means for supporting the forward end of said trough on said cutter head for pivotal movement with respect thereto, and means for adjustably supporting the rearward end of said trough on said mining machine.

3. In combination with a track mounted mining machine having a depending cutter head, a cutter bar projecting forwardly therefrom having a cutter chain movable thereabout adapted to cut a kerf adjacent the mine bottom, conveying means wholly supported by said mining machine for clearing the cuttings from the path of said cutter chain comprising an inclined trough having a forward end engageable with the mine bottom adjacent the path of said cutter chain and having a conveyor therein, and means for supporting said trough in an inclined position with respect to said mining machine for pivotal movement with respect thereto.

4. In combination with a track mounted mining machine having a depending cutter head, a cutter bar projecting forwardly therefrom having a cutter chain movable thereabout adapted to cut a kerf adjacent the mine bottom, conveying means wholly supported by said mining machine for clearing the cuttings from the path of said cutter chain comprising an inclined trough having a forward end engageable with the mine bottom adjacent the path of said cutter chain

- and having a conveyor therein, and means for supporting said trough in an inclined position with respect to said mining machine for pivotal movement with respect thereto comprising supporting means supported on said cutter head and engageable with the forward end of said trough. 5
5. In combination with a track mounted mining machine having a depending cutter head, a cutter bar projecting forwardly therefrom having a cutter chain movable thereabout adapted to cut a kerf adjacent the mine bottom, conveying means for clearing the cuttings from the path of said cutter chain comprising an inclined trough having a forward end engageable with the mine bottom adjacent the path of said cutter chain and having a conveyor therein, and means for supporting said trough in an inclined position with respect to said mining machine for pivotal movement with respect thereto comprising supporting means supported on said cutter head and engageable with the forward end of said trough, and connecting means extending from said mining machine to said conveying means rearwardly of said trough. 15
25. 6. In combination with a mining machine, a cutter head having a cutter bar projecting therefrom, a cutter chain movable thereabout adapted to cut a kerf adjacent the mine bottom, conveying means for clearing the cuttings from the path of said cutter chain comprising an inclined trough having a forward end engageable with the mine bottom adjacent the path of said cutter chain and having a spiral conveyor therein, and means for supporting said trough in an inclined position with respect to said mining machine for pivotal movement with respect thereto comprising supporting means supported on said cutter head and engageable with the forward end of said trough, and connecting means extending from said mining machine to said conveying means rearwardly of said trough and having adjustable connection with said conveying means for varying the angle of inclination of said trough with respect to said mining machine. 30
45. 7. In combination with a track mounted mining machine adapted to cut a kerf adjacent the mine bottom having a chain carrying projecting cutter bar, an inclined trough supported on said mining machine adjacent the retreating side of said cutter bar for pivotal movement with respect thereto and having a receiving end disposed adjacent the mine bottom, means cooperating with the cutter chain on said cutter bar for deflecting the cuttings into the receiving end of said trough, and a spiral conveyor in said trough for discharging the cuttings therefrom beyond said mining machine. 50
55. 8. In combination with a track mounted mining machine having a depending cutter head, a cutter bar projecting forwardly of said cutter head having a cutter chain movable thereabout, a trough supported on said cutter head adjacent the retreating side thereof and having a receiving end disposed adjacent the mine bottom, means cooperating with said cutter chain for deflecting the cuttings into the receiving end of said trough, and a spiral conveyor in said trough for discharging the cuttings therefrom beyond said cutter head. 60
65. 9. In combination with a track mounted mining machine having a depending cutter head, a cutter bar projecting forwardly of said cutter head having a cutter chain movable thereabout, an inclined trough supported on said cutter head adjacent the retreating side thereof for pivotal movement with respect thereto and having a re-
- ceiving end disposed adjacent the mine bottom, means cooperating with said cutter chain for deflecting the cuttings into the receiving end of said trough, and a spiral conveyor in said trough for discharging the cuttings therefrom beyond said cutter head. 70
75. ceiving end disposed adjacent the mine bottom, means cooperating with said cutter chain for deflecting the cuttings into the receiving end of said trough, and a spiral conveyor in said trough for discharging the cuttings therefrom beyond said cutter head. 80
10. In combination with a track mounted mining machine having a depending cutter head, a cutter bar projecting forwardly of said cutter head having a cutter chain movable thereabout, an inclined trough supported adjacent its forward end on said cutter head adjacent the retreating side thereof for pivotal movement with respect thereto and having a receiving end disposed adjacent the mine bottom, said trough being supported adjacent its rearward end by pivotally movable supporting means connected with said mining machine, means cooperating with said cutter chain for deflecting the cuttings into the receiving end of said trough and a spiral conveyor in said trough for discharging the cuttings therefrom beyond said cutter head. 85
15. 11. In combination with a track mounted mining machine having a depending cutter head, a cutter bar projecting forwardly of said cutter head having a cutter chain movable thereabout, an inclined trough supported adjacent its forward end on said cutter head adjacent the retreating side thereof for pivotal movement with respect thereto and having a receiving end disposed adjacent the mine bottom, said trough being supported adjacent its rearward end by pivotally movable supporting means connected with said mining machine, means cooperating with said cutter chain for deflecting the cuttings into the receiving end of said trough, a conveyor in said trough for discharging the cuttings therefrom beyond said cutter head, and means connectable with said trough for pivotally moving said trough with respect to said cutter head and controlling the point of discharge of said cuttings from a point remote from said cutter head. 90
20. 12. In a mining machine adapted to be mounted on and cut from the track, a forwardly projecting cutter bar having a cutter chain movable thereabout for cutting a horizontal kerf in the mine wall, and means wholly supported by said mining machine for clearing the cuttings from the path of said cutter chain comprising a spiral conveyor supported on said mining machine and attached thereto adjacent the rearward retreating side of said cutter chain for pivotal movement with respect thereto about a vertical axis. 105
25. 13. In a mining machine, a horizontally disposed cutter bar having a cutter chain movable thereabout adapted to cut a horizontal kerf in the mine wall, conveying means for clearing the cuttings from the path of said cutter chain comprising an inclined trough having a conveyor therein, said trough having a lower receiving end in alignment with the rearward retreating side of said cutter bar, said inclined trough being adjustably supported on said mining machine for pivotal movement with respect to said cutter bar about a vertical axis disposed adjacent the lower end of said trough and about an axis inclined with respect thereto for varying the angle of inclination of said trough and being adjustably supported adjacent its upper end on said mining machine. 110
30. 14. In a track mounted mining machine, a truck, a cutter bar projecting therefrom, a cutter chain movable about said cutter bar for cutting a horizontal kerf in the mine wall, an inclined trough supported on said mining machine ad-
- 115
- 120

jacent the retreating side of said cutter bar for pivotal movement with respect thereto and having a receiving end disposed adjacent the mine bottom, means cooperating with said cutter chain for deflecting the cuttings into the receiving end of said trough, and a spiral conveyor in said trough for discharging the cuttings therefrom beyond said mining machine.

15. In a mining machine, the combination of 10 horizontal cutting mechanism including a cutter bar having a cutter chain movable thereabout and a cuttings collecting and distributing device associated with said cutter bar including a trough wholly supported by said mining machine and 15 having a receiving end disposed adjacent the rearward retreating side of said cutter bar, means cooperating with said cutter chain for deflecting the cuttings into the receiving end of said trough, and a spiral conveyor in said trough for discharging the cuttings therefrom beyond said cutter bar.

16. In a mining machine, the combination of 20 horizontal cutting mechanism including a cutter bar having a cutter chain movable thereabout and a cuttings collecting and distributing device associated with said cutter bar including a trough wholly supported by said mining machine for pivotal movement with respect thereto in both

horizontal and vertical planes and having a receiving end disposed adjacent the rearward retreating side of said cutter bar, means cooperating with said cutter chain for deflecting the cuttings into the receiving end of said trough, and a spiral conveyor in said trough for discharging the cuttings therefrom beyond said cutter bar.

17. In a mining machine, the combination of 25 horizontal cutting mechanism including a cutter bar and a cuttings collecting and distributing device associated with said cutter bar including a trough wholly supported by said mining machine for pivotal movement with respect thereto in both horizontal and vertical planes and 30 having a receiving end disposed adjacent the rearward retreating side of said cutter bar, means cooperating with said cutter chain for deflecting the cuttings into the receiving end of said trough, and a conveyor in said trough for discharging the cuttings therefrom beyond said cutter bar, and means connectible with said trough for pivotally moving said trough with respect to said cutter head and controlling the point of discharge of said cuttings from a point remote 35 from said cutter head.
